UNITED STATES PATENT OFFICE.

HARRY C. RADCLIFFE, OF PHILADELPHIA, PENNSYLVANIA.

DESIGN FOR AN ANTIRATTLER FOR WINDOW-SASHES.

SPECIFICATION forming part of Design No. 34,442, dated April 30, 1901.

Application filed March 1, 1901. Serial No. 49,514. Term of patent 7 years.

To all whom it may concern:

Be it known that I, HARRY C. RADCLIFFE, a citizen of the United States, residing in the city and county of Philadelphia, State of Pennsylvania, have invented and produced a new and original Design for Antirattlers for Window-Sashes, of which the following is a specification, reference being had to the accompanying drawings, forming part thereof.

10 The leading feature of my design for an antirattler for a window-sash is a body formed of side wedge-shaped members and a narrow neck extending in the longitudinal direction of the body from one side member to the other at the center thereof, presenting at the 15 butt of the body the appearance of an H-shaped figure.

Figure 1 represents a perspective view of an antirattler for a window-sash embodying

my design. Fig. 2 represents a section thereof on line $x-x$, Fig. 1.

In the drawings, A designates the body of the antirattler, the same consisting of the wedge-shaped members B at the sides thereof and the neck C, which extends in the longitudinal direction of the body from the center of one side member to the other, presenting at the butt of the body the appearance of an H-shaped figure.

Having thus described my invention, what I claim as new, and desire to secure by Letters Patent, is—

The design for an antirattler for a window-sash substantially as shown and described.

HARRY C. RADCLIFFE.
